UNITED STATES PATENT OFFICE.

JOSEPH H. BOURGON, OF DETROIT, MICHIGAN, ASSIGNOR TO THE STUDEBAKER CORPORATION, OF SOUTH BEND, INDIANA, A CORPORATION OF NEW JERSEY.

TOP CONSTRUCTION.

Application filed October 30, 1924. Serial No. 746,876.

This invention relates to tops for motor vehicles and particularly to that class of tops provided with continuous coved sheet metal side quarters, as illustrated and described in my co-pending patent application on top construction filed July 9, 1924, Serial Number 725,062, and in respect to which this invention constitutes an improvement.

It is an object of this invention to provide stiffening members for the side quarters of such a top whereby the same will be materially strengthened.

Another object is to provide stiffening members formed to match the interior of the quarters in a plane transversely to the length of the quarters and to be secured in matching relation therein.

Another object is to provide such stiffening members of sheet metal, the edges of which are bent perpendicularly to the face of the member to provide attaching and securing flanges whereby the same is secured to the top supporting member.

A still further object is to provide such stiffening members which will also serve as supports for the curtains of said top, and also provide means for supporting a curtain shield or other such parts as it may be found desirable.

The above being among the objects of the present invention, the same consists of certain features of construction and combinations of parts to be hereinafter described, with reference to the accompanying drawings and then claimed, having the above and other objects in view.

In the accompanying drawings, which illustrate a suitable embodiment of the present invention, and in which like numerals refer to like parts throughout the several views,

Figure 1 is a perspective view of an automobile top frame to which this invention is particularly adaptable.

Figure 2 is a view, taken from the inside of the right hand quarter of the frame illustrated in Figure 1, showing the position of stiffening bracket members therein.

Figure 3 is a fragmentary perspective view of a portion of one of the top frame side quarters showing the forward stiffening bracket member secured in operative position therewith.

Figure 4 is an enlarged horizontal sectional view taken in the line 4-4 of Figure

10 showing the forward stiffening bracket member.

Figure 5 is a fragmentary perspective view of a portion of one of the top frame side quarters, showing the rear stiffening bracket member secured in operative position therein.

Figure 6 is a view looking from the inside of the front portion of the right hand top frame side quarter showing the bracket for supporting the forward end of the front curtain.

Figure 7 is a sectional view taken on the line 7-7 of Figure 6, showing a face view of the bracket.

Figure 8 is a perspective view of the forward stiffening bracket member.

Figure 9 is a perspective view of the curtain support attached from the stiffening bracket.

Figure 10 is a sectional view taken through the right hand forward stiffening bracket member in a plane parallel to its face, showing the manner of supporting the curtain shield tacking strip thereby and also the manner of supporting the curtain shield stiffening member, the curtains being shown diagrammatically by dotted lines.

Figure 11 is a fragmentary perspective view of the right hand top frame side member, showing the several parts in operative relation therewith.

In the drawings is illustrated a frame of a permanent top for an automobile of substantially the same general construction as that shown and described in my application for United States Letters Patent on top constructions, filed July 9, 1924, Serial No. 725-062, above referred to. In order to facilitate cross reference between the former application and the present one, the reference numerals in this application correspond to the reference numerals in the earlier application as far as possible.

The top frame essentially comprises side quarters 30, rear quarter 31, front cross member 32 and ribs 33. Posts such as 47 are provided at the front end of the frame for supporting the front end of the top, and other posts such as 48 are provided forward of the rear end of the frame for carrying the greater part of the weight of the top, curved sheet metal members such as 64 being provided at the rear corners and extending down from the top frame to the body.

to act as a forming member for the top covering when applied.

The quarters 30 are preferably formed of sheet metal which are curved to conform 5 to the shape of the top quarters and extend continuously from the front support 32 to the rear quarter 31. The rear quarter 31 is also curved to conform to the shape of the side quarters and is formed to blend into 10 and to be secured by suitable means thereto. The upper inner edges of the quarters 30 are bent downwardly and then bent inwardly to form a horizontally extending flange 84 to which are secured the ends of the ribs 33 15 which extend from one quarter over to the other quarter and act to support the top covering when applied. The lower edge of each quarter is turned inwardly to form a horizontally extending flange 83 to which 20 the top rear support 48 is secured and to which a tacking strip 62, for the top covering, is also secured. Two rollers curtains 41 are shown mounted in overlapping relation within each quarter 30 and are capable of 25 being unrolled to form a closure between the front supports 47 and rear supports 48, grooves 52 being provided in the front supports 47 and grooves 54 being provided in the rear supports 48 to receive and guide 30 the adjacent edge of the adjacent curtain.

The curtains 41 are supported within the quarters 30 by suitable brackets, the front edge of the front curtain being supported by a strip 96 (Figures 6 and 7) extending 35 vertically at the front end of the quarter 30 from the upper edge thereof down to the angle iron member 36 which is employed to tie the side quarters 30 to the front cross member 32, a suitable opening 97 being provided in the strip 96 to receive the conventional axle pin on the end of the curtain roller. The rear end of the front curtain is suitably supported in a small bracket 39 40 welded or otherwise secured to the inner face of the quarter 30.

The bracket 46 for the front end of the rear curtain is secured to the inner side of the quarter 30 forward of the rear end of the front curtain so that the front and rear 50 curtains will overlap along their adjacent edges and will form a tight and effective joint to exclude the weather when in unrolled position. The rear end of the rear curtain is suitably supported in a bracket 55 98 somewhat similar to the bracket 46.

It is in connection with such brackets as 46 and 98 that this invention is concerned and accordingly they will be described in detail. Each is preferably formed of sheet metal as shown, the attaching edge being shaped to conform to the interior surface of the quarter 30 and the remaining edges being formed to suit such purposes as may be found desirable. The metal around the entire periphery of the brackets is prefer-

ably bent perpendicular to the face thereof to provide attaching flanges 99 and for materially increasing the strength thereof. The flange 99 along the edge matching the inner surface of the quarter 30 is secured thereto 70 by spot welding or other suitable means and because of its shape and strength acts to hold the quarter 30 to its proper shape and also considerably stiffens the same and increases its resistance to the different strains 75 to which it may be subjected. For the purpose of supporting the curtain 41 each bracket 46 is provided with a rectangular opening 100 in its face and a U-shaped strip member 101 having outwardly turned free 80 edges is inserted in the opening and the free edges are secured to the face of the brackets by spot welding or the like. The bottom of the U is provided with a slot for receiving and supporting an end of the curtain 85 roller.

The remaining edge of the brackets 46 and 98 may be formed to suit any purpose desired as before stated. As illustrated, the remaining edge of each bracket 98 is for the greater part of its length formed straight, leading from the lower flange 83 of the quarter 30 upwardly and inwardly to a point near its upper surface, from whence it is turned inwardly to form a projection which lies adjacent the upper flange 84. The flanged edge 99 of this straight part is provided with an opening 102 in the upper portion thereof and a tapped block 103 is secured to the flange 99 back of the opening in such a manner that a screw may be inserted through the opening 102 and threaded into the block 103. Such means is utilized for supporting the longitudinally extending wooden member 43 to which is attached the upper edge of the curtain shield 45 which extends downwardly therefrom to a point adjacent the tacking strip 62 where it acts as a guide for the curtains 41 when the curtains are being unrolled and also conceals the curtains 41 in the quarters 30, when they are in rolled position. Aside from securing the flange 99 to the curved portion of the side quarter 30 by spot welding or other means, the bracket 98 may also be secured 115 to the flange 83 and also to the depending portion at the upper and inner edge of the quarter 30 to thus more securely brace the quarter intermediate its ends.

The bracket 46, although conforming to the contour of the interior of the quarter 30, does not extend down to the flange 83 because of the necessity of clearing the front curtain 41 which is positioned below the rear curtain. Its unattached edge is formed to clear the front curtain and is also formed with an upper depression 103 which receives the longitudinally extending wooden member 43 and which is secured thereto in a manner similar to that by which it is at 120 125 130

tached to the rear bracket 98 or by simply inserting a bolt 104 through the wooden member 43 and through the block 105 after which a nut 106 is threaded on the end projecting through the block 105 as shown in Figure 10. The flange 99 immediately below the depression 103 is backed by a tapped block 107 to which is secured by the screws 108 the arm 94 which is welded to the stiffening rod 90, disposed in the lower edge 10 of the shield 45, and which forms a stiffening member for the same.

Although but three specific uses of the brackets 46 and 98, besides their primary use of strengthening the top, are illustrated and described, it will be apparent that such brackets may be modified to meet a variety of these and other uses, and I do not limit myself to the specific construction and application shown but claim broadly as my invention that which is commensurate with the appended claims.

What I claim is:

1. The combination with a vehicle top having continuous coved sheet metal side quarters, of means for stiffening said quarters comprising transversely positioned brackets having one face conforming in shape and secured to the interior surface of said quarters and having a second face formed to provide an attaching member for a curtain shield.

2. The combination with a vehicle top having coved sheet metal side quarters, of a brace therefor positioned therein comprising brackets formed of sheet metal and having a flange bent out of the plane of the body thereof to conform to the shape of said quarters and secured thereto, said flange also providing an attaching face on the side opposite the face attached to said quarters, and a shield for concealing said brace and side quarter secured to said attaching face.

3. The combination with a vehicle top having coved sheet metal side quarters, of brackets positioned transversely thereof conforming in shape to the interior surface of said quarters and secured thereto along the matching edges of said quarters and brackets and means carried by said brackets for supporting vehicle side enclosures.

4. The combination with a vehicle top having coved sheet metal side quarters, of brackets positioned transversely of said quarters and conforming in shape to said quarters and secured to the interior surface thereof, and brackets carried by first mentioned brackets for supporting roller curtain side enclosures.

5. The combination with a vehicle top having curved sheet metal side quarters and transversely positioned brackets matching the interior surface of said quarters and secured thereto in matching relation, of

means for supporting roller curtain side enclosures on said brackets, and separate means carried by said brackets for concealing said roller curtains when in rolled position.

6. In combination with a vehicle top having coved sheet metal side quarters provided with flanges at the upper and lower edges thereof, brackets positioned transversely of said side quarters intermediate the ends thereof which conform in shape and are secured to the curved portion and to said flanges of said side quarters, and means for supporting body enclosures on said brackets.

7. In combination with a vehicle top having coved sheet metal side quarters, braces secured to said quarters transversely thereof and intermediate the ends of said quarters, said braces having flanges thereon conforming in shape with the curved surface of said quarters and secured to said curved surface, each brace forming the support for an end of a roller curtain and provided with means for securing a tacking strip thereto, and a shield for said curtain attached to said tacking strip.

8. In combination with a vehicle top having coved sheet metal side quarters, braces positioned transversely of said side quarters and secured thereto intermediate the ends thereof, said braces each having a flat, free surface to which is secured a shield spaced from and on the inner side of said side quarters.

9. In a vehicle top having coved sheet metal side quarters adapted to support a plurality of roller curtains in overlapping relation, brackets forming stiffening members for said quarters secured thereto, said brackets being spaced to support one of said curtains and one of said brackets being formed to provide clearance for another of said curtains to position the same in overlapping position.

10. In a vehicle top having coved sheet metal side quarters, braces for said side quarters conforming in shape with and secured transversely thereto, and brackets offset from and secured to said braces for supporting side closures thereon.

11. In combination with a vehicle top having sheet metal side quarters and a member at the front of said top intermediate said side quarters, means for connecting said member and said side quarters, a bracket secured to said means forming the support for the front end of a side curtain, a block carried by said side quarter for supporting the other end of said curtain, and braces for said side quarter secured thereto intermediate its ends and forming the support for a second curtain, one of said last-named braces being shaped to provide clearance for said first-named curtain to position said curtains in overlapping relation.

12. In combination with a vehicle top

having sheet metal side quarters, a brace secured to each of said quarters intermediate the ends thereof, members connecting the front and rear ends of said side quarters, a bracket supported by each of said side quarters, a bracket supported at the front of each of said side quarters, and a block secured to each side quarter, said block and

said second named bracket being adapted to support a curtain therebetween, and said brace and said first named bracket supporting a second curtain in overlapping relation with said first named curtain.

Signed by me at Detroit, Michigan, U. S. A., this 27th day of October, 1924.

JOSEPH H. BOURGON.
